ELIMINATION AND IRRIGATION EQUIPMENT

Evie R. Seymour and Charles W. R. Russell,
Portsmouth, Va.

Application September 30, 1947, Serial No. 777,030

1 Claim. (Cl. 4—112)

1

The present invention relates to elimination and irrigation equipment and it consists in the combinations, constructions and arrangements of parts herein described and claimed.

Generally there is provided a device for use by colostomy patients which will provide them with means whereby successful and proper elimination of waste body material may be had. The device is so constructed that it may be utilized with a conventional commode, with an especially provided bed pan or as a compact unit. It consists essentially of a funnel-like member, one side of which is adapted to be held firmly against the body of the patient and the other side of which is provided with an extended apron which is normally spaced from the patient's body so that he may be free to insert irrigation equipment therethrough to the colostomy. The neck of the funnel-like member may empty directly into a commode or may be connected by extension tubing which is provided as a part of the invention to an especially constructed receiving chamber. Again, the neck may be placed within a bed pan forming a part of the invention and which possesses in itself several novel features.

It is accordingly an object of the invention to provide a device of the character set forth which is simple in construction and operation and yet effective and efficient in use.

Another object of the invention is the provision of a device of the character set forth in which the use of a patient's hands is unnecessary for holding the device in proper operative position.

A further object of the invention is the provision of a device of the character set forth, the use of which will allow a colostomy patient to completely relax, both mentally and physically during the self-administration of an enema.

Another object of the invention is the provision of a funnel-like member having a body engaging portion and an apron portion.

Another object of the invention is the provision of means for coupling the funnel-shaped member to a novel portable receiving apparatus forming a part of the invention.

A still further object of the invention is the provision of a novel bed pan forming a part of the invention.

Other and further objects of the invention will become apparent from a reading of the following specification taken in conjunction with the drawings, in which:

Figure 1 is an elevational view of an embodiment of the invention.

Figure 2 is a plan view of Figure 1.

2

Figure 3 is a sectional view taken along line 3—3 of Figure 2.

Figure 4 is a side elevational view, partly fragmentary, of a modified form the invention may take, and

Figure 5 is a fragmentary elevational view of an element of the invention.

Referring more particularly to the drawings, there is shown therein a funnel-like member generally designated at 10 and having an angularly extending body engaging portion 11 and a substantially vertically extending apron portion 12. There is also provided a neck 13.

The upper edges of the funnel-like member 10 are provided with a continuous bead 14 and the upper edges of the body engaging portion 11 are provided with relatively high sides 15 and 15' and a depressed center 16. The upper edge of the portion 12 is relatively higher than the upper edges of the portion 11, and the side or end 15 is relatively higher than the side 15'.

A bed pan 18 of elongated contour is provided at one end with a handle 19 and with a handle 20 upon one side thereof adjacent the other end of the same. That end of the pan provided with the handle 19 is relatively higher than the other end of the pan which is provided with an integrally formed lip 21, and one side of the pan is inwardly rounded, as indicated at 22.

In Figure 4 there is shown a special portable container 23 preferably formed of glass and provided with a screw cap 24 having a centrally upwardly extending pipe 25 and in Figure 5 there is shown an angular extension 26 for the neck 13.

In operation, it will be apparent that if the device is to be used in conjunction with a conventional commode that the funnel-like member 10 is used alone. In any event the portion 11 is placed beneath the colostomy and firmly and snugly against the abdomen of the user in the manner disclosed in Figure 3. Because of the angular disposition of the portion 11 the apron 12 will be spaced from the body of the user and, because of its relatively high upper edge 17, it will allow the insertion of a catheter into the patient's colostomy. Again, since the edges 15 and 16 are engaged with the abdomen of the user, the neck 13 will extend downwardly into the commode and it will be unnecessary for the patient to utilize either or both of his hands to hold the same in this position thus leaving him free to administer the irrigation.

In the case of a bed patient the funnel will be used with the bed pan 18, in the manner shown in Figure 3. The rounded indentation 22 extending

55

along one side of the bed pan 18 will allow the patient a closer approach to the effective portions of the apparatus and the pan 18 will be so placed that its deeper end will compensate for the lowering of the bed upon which the patient rests due to the depression thereof on account of the weight of the patient. The lip 21 is provided for emptying the pan 18 in a neat manner.

The extension 26 may be locked upon the neck 13 by means of the bayonet type lock joint when the patient is using the conventional commode and will direct the matter passing therethrough against the wall of the commode thereby preventing splattering and splashing to the discomfort of the patient. The device also helps to 15 keep the commode in a clean condition.

When the device is utilized with the container 23, the neck 13 may be locked with the pipe 25 by means of the bayonet type joint shown and the patient may utilize an ordinary chair in such 20 case when administering an enema. If need be to secure proper height for the funnel-like member 10 an interconnecting pipe may be connected with the neck 13 and the pipe 25.

While but certain forms of the invention have 25 been shown and described herein, it will be readily apparent to those skilled in the art that many minor modifications may be made without departing from the spirit of the invention or the scope of the appended claim.

We claim:

A device for use in the administering of an enema to a colostomy patient comprising a receptacle, said receptacle being substantially el-

liptical shape in plan, one end of the ellipse being substantially higher than the opposite end and one side edge of the ellipse being substantially lower than the other side edge and lower than said opposite end, said lower edge adapted to be held against and follow the contour of the body of the user in the region of the colostomy opening with said other side edge and ends of the receptacle serving as a shield, and a discharge spout connected to the base of said receptacle.

EVIE R. SEYMOUR.
